UNITED STATES PATENT OFFICE.

THOMAS L. TALIAFERRO, OF LA GRANGE, ILLINOIS.

VACUUM SEALING-MACHINE.

1,245,063.

Specification of Letters Patent. Patented Oct. 30, 1917.

Application filed July 1, 1915. Serial No. 37,517.

To all whom it may concern:

Be it known that I, THOMAS L. TALIAFERRO, a citizen of the United States, residing at La Grange, in the county of Cook 5 and State of Illinois, have invented certain new and useful Improvements in Vacuum Sealing-Machines, of which the following is a specification.

The present invention relates to a machine 10 for sealing receptacles by the vacuum process.

The objects of the invention are to provide a machine equipped with a vacuum regulator, whereby a means for affixing in 15 place the closure of the receptacle is actuated when a predetermined degree of vacuum has been created within the vacuum chamber in which the receptacle is located.

A further object of the invention is to 20 provide a simple and quick method of adjusting a controlling member for the vacuum regulator to vary the degree of vacuum which will be created in said receptacle chamber at the time said closure affixing 25 means is actuated.

A further object of the invention is to provide a clutch mechanism actuated by the movements of the vacuum regulator, the actuation of which clutch mechanism will 30 start the operation of the closure affixing mechanism.

A further object of the invention is to automatically return said closure affixing mechanism to normal position when its operation upon the receptacle has been completed and to move other parts of the machine to expose the receptacle being operated upon and allow of its removal and the placing in position of another receptacle. 35

40 A further object of the invention is to provide means for automatically cutting off the vacuum prior to the completion of the operation of the closure affixing mechanism.

A further object of the invention is to 45 move certain of the parts to form the vacuum chamber without affecting any movement of the closure affixing means.

The invention further consists in the features of construction and combinations of 50 parts hereinafter described and claimed:

In the drawings:

Figure 1 is a side elevation of the machine of the present invention;

Fig. 2 is a front view of the parts shown 55 in Fig. 1;

Fig. 3 is a section taken on line 3—3 of

Fig. 1 showing the member which constitutes the receptacle vacuum chamber in lowered position by means of full lines and in raised position by means of dotted lines; 60

Fig. 4 is a view of the parts shown in the upper portion of Fig. 3 with the member constituting the receptacle vacuum chamber in raised position and the closure affixing member in downward or acting position; 65

Fig. 5 is a detail view showing the means for cutting off the vacuum at the instant of cut-off;

Fig. 6 is a detail view partly in section 70 showing the connection between the vacuum controlling member and the clutch mechanism and showing the clutch mechanism in retracted position; and

Fig. 7 is a view similar to Fig. 6, showing the clutch mechanism released and in operative position.

As previously stated, the present invention relates to a machine for sealing receptacles by the vacuum process. In the sealing of receptacles by this process, it is very desirable, especially when certain substances are contained within the receptacle, to affix the closure in place when a certain degree of vacuum is reached, and one feature of the 80 present invention deals with a machine which may automatically complete the closure affixing operation, when a predetermined amount of vacuum has been reached.

Referring to the drawings, the operative 90 parts are carried by a frame 8 which may be of any suitable size and construction, comprising, as shown, a base 9 and outwardly extending arms 10 and 11 terminating in sleeves 12 and 13 respectively. The frame 95 also contains an upwardly extending standard or support 14. Pivoted to the lower portion of the frame 8 is a foot lever 15 which may be termed the actuating member of the machine, since this member 100 may be shifted, or moved by the operator, to start the sealing operation. The foot lever is connected by a link 16 to a lever 17, pivoted at 18, and said lever has affixed to one arm a weight 19, and the other arm 20 of 105 said lever terminates in a forked end 21. Each branch or arm of the forked end is slotted, as at 22, and lying within these slots are pins 23 extending from a cup-shaped member 24, which may be termed the vacuum bell.

This bell is movable or shiftable vertically

and when raised it forms a chamber about the receptacle which may be termed the receptacle vacuum chamber. The bell carries a packing gland 25 at its lower end, and a 5 compressible sealing or packing ring 26 at its upper end. This bell is guided in its movement by a fixed tubular member 27 which may be termed a vacuum duct and this duct communicates at its lower end with 10 a cylinder 28 into which leads an exhausting pipe 29. The duct 27 is, as will be seen from Fig. 3, rigidly held within the sleeve 12 and therefore maintains a fixed position. At the upper end of the tubular member 27 15 is a nozzle 30 provided with a vertical bore 31, and cross or horizontal bores 32 which communicate with the vertical bore 31 and with the interior of the vacuum bell, and carried by this nozzle is a head 33 which constitutes a receptacle support.

Located above the vacuum bell 24 and receptacle support 33 is a rod or plunger 34 which has a sliding fit in the sleeve 13 and is guided in its movements by such sleeve. 25 This plunger is affixed at its lower end to a chambered member 35 which may be termed the receptacle closure affixing member, since it is this member which carries the mechanism that crimps the receptacle 30 closure and affixes it to the receptacle. The closure affixing mechanism comprises a coil spring 36 surrounding a movable head 37, which head is held normally downward by the action of springs 38. The closure affixing member in addition to the function above attributed to it, namely, fixing the closure in position on the receptacle, also co-operates with the vacuum bell to form a receptacle vacuum chamber as will herein- 35 after appear. As stated, communicating with the interior of the cylinder 28 is an exhausting pipe 29, which pipe extends to a valve 40 of the ordinary two way type, and also communicating with this valve is the 40 main exhausting pipe 41 leading from any suitable exhauster. An emergency relief pipe 39 extends from the cylinder 28, which pipe is equipped with a valve 39a.

Branching from the pipe 29 is a pipe 42 45 which communicates with the interior of a chambered member 43, within the chamber of which is located a piston 44 and this piston and chambered member, together with the associated parts, serve to control or limit the vacuum to which the receptacle will be subjected; that is to say these parts control 50 the operation of the closure affixing means, whereby said means operate when a certain and predetermined degree of vacuum has been created within the vacuum chamber of the sealing appliance. Extending from the piston 44 is a stem 45, to which is connected a rod 46, said connection, in the construction shown, being of swivel form. The rod 46 55 travels through guides 47 of a standard or

support 48, and is normally sustained in raised position by a tension member 49.

To the end of this rod 46 is attached a clutch controlling member 50, composed of a body portion carrying a roller or stud 51 70 and a finger 52. It will be understood, however, that this particular type of clutch control, as well as the hereinafter described type of clutch has been used in connection with other machines, and no claim of novelty 75 is made to the particular form of clutch control and clutch illustrated, except as a clutch or clutch control may be claimed in combination with other elements.

The particular clutch illustrated in the 80 drawings embodies a movable section 53 and a fixed section 54, each formed with suitable clutch surfaces. The section 53 is formed with a cam ring 55 against the edge of which engages the roller 51, and a groove 56 is 85 formed in said movable clutch member in which engages the finger 52; springs 57 are provided for forcing the movable clutch member into engagement with the fixed clutch member when the clutch controlling 90 means are released.

Connected to the fixed clutch member 54 is a main driving pulley 58, and the movable clutch member 53 is splined or otherwise suitably secured to a shaft 59, to which shaft 95 is connected a cam 60 and an eccentric 61. In the construction shown, the particular shaft is also equipped with a suitable hand wheel 62. The cam 60 is in peripheral engagement with a roller 63, carried upon 100 the end of a pivoted arm 64, which arm is pivoted at 65, and said arm is formed with a slot 66 at the other end from that which carries the roller 63, in which slot rests a pin 67, extending from a block 68. This 105 block is attached to the rod or plunger 34. Extending from the eccentric 61 is a rod 69 attached to a swinging member 70, the actuation of which cuts off the exhaust by means of the valve member 40. The valve 110 40 is actuated to permit the exhaust therethrough, by means of pivoted link members 71, which are moved into position to establish the exhaust connection through the valve member by a contact 72 on the arm 20 115 of the lever 17.

Extending from the cylinder 43 is a supporting member 73, to which is pivotally attached an arm 74, carrying a weight 75 on one end thereof, which weight is adjustable along the length of said arm. The arm 74 suitably engages at its other end 76 with the stem 45 of the piston 44. The operation of the machine is as follows:

A receptacle with a closure loosely fitted 125 thereon is first placed on the receptacle support 33. The foot treadle 15 is then depressed, pulling downward the rod 16, which swings the lever 17 in a manner to pull down the weight 19 and raise the arm 20 thereof. 130

By the raising of the arm 20 the contact 72 engages with and moves the pivoted link members 71, and actuates the valve 40 to establish communication through said valve 5 with the main vacuum exhausting pipe 41. The arm 20 in moving upward, moves the vacuum bell 24 from the position shown in full lines in Fig. 3 to that shown in dotted lines in the same figure, and when fully 10 raised, as will be seen from the drawings, the packing ring 26 engages with the lower face of the closure affixing member 35 whereby a closed chamber is formed about the receptacle.

15 When the vacuum bell is raised, as shown by dotted lines in Fig. 3, and a receptacle vacuum chamber is formed, the valve 40 will have been actuated to establish communication with the main vacuum exhaust 41 so 20 that the air is exhausted through the pipes 39 from the interior of the cylinder 28, and through the vacuum duct 27, and the nozzle 30 thereof from the interior of the vacuum bell 24, creating a vacuum within the receptacle vacuum chamber. This vacuum will exert its influence upon the interior of the receptacle to be sealed, owing to the loose fit of the receptacle closure, creating a vacuum within the receptacle. At the same time 25 that the valve 40 is actuated to establish communication between the valve passages and the pipes 29 and 27, to establish communication between the main exhaust and the receptacle vacuum chamber to create 30 a vacuum within this chamber, a vacuum is also created in the cylinder 43.

The piston 44, which travels within this cylinder, is normally held in raised position, being the position shown in Fig. 6, by 35 the influence of the weight 75, as will be obvious from the drawings. When a sufficient degree of exhaustion has been reached within the cylinder 43, beneath the piston 44, to draw downward the said piston 45 against the force exerted by the weight 75, the piston will be drawn down into the position shown in Fig. 7. It is thus obvious that by placing the weight 75 a lesser or greater distance from the pivotal point or 50 fulcrum of the valve 74, the piston will be pulled downward by a lesser or greater degree of exhaustion according as the weight is closer or farther away from said pivoted center. Thus by the adjustment of this 55 weight the amount of vacuum created in the vacuum bell or sealing chamber, before the closure affixing member is set into operation, is controlled and depends entirely upon the position of this weight member 75.

60 So that the amount of vacuum created within the to-be-sealed receptacle prior to the affixing of the receptacle closure can be accurately determined by the proper positioning of this weight 75.

65 When the piston 44 is drawn downward, it pulls downward the rod 46 into the position shown in Fig. 7. This releases the movable clutch member 53 so that it moves into engagement with the fixed clutch member 54, as shown in Fig. 7, and by the rotation of the driving pulley 58 the shaft 59 is rotated rotating the cam 60. By reason of the configuration of this cam the roller 63 will be moved upward moving upward that portion of the lever 64 to which the roller 70 is attached, and moving downward the other end of the lever 64, which, by reason of its connection with the plunger 34, thus forcing down said plunger, which forces down the closure affixing member 35. This closure 75 affixing member and the vacuum bell will move downward in unison for a predetermined distance, until the vacuum affixing member has reached the position shown in Fig. 4, wherein the spring 36 has acted to 80 crimp the cap or closure of the receptacle and affix it in place.

When the above described operation is complete, the eccentric 61 will actuate the rod 69 to move the shiftable member 70, and 85 cut off the exhausting connection through the valve 40 and open up a suitable exhaust, such as is well known in two way valves. This will result in a breaking of the vacuum both in the vacuum bell and in 90 the cylinder 43, relieving the suction below the piston 44 and the weight 75 will then act to lower that portion of the lever 74 on which it is mounted, raising the end 76 of the lever, lifting the piston 44 and the stem 95 46, and moving the clutch controlling member back into the position where the roller 51 will engage with the cam surface 55 and throw the clutch back into the position shown in Fig. 6. This will break the connection between the fixed and movable clutch members, and stop the rotation of the shaft 59, and when the rotation of said shaft is stopped the parts will be in the position 100 shown in Fig. 1. A spring 80 acts to maintain the roller 63 against the periphery of the cam 60, and hence when the cam has made a complete revolution the lever 64 is thrown into the position shown in Fig. 1 and the closure affixing member 35 is raised. 105

When the foot treadle 15 is lowered, the vacuum bell 24 will be raised upwardly around the jar standing on the table 33, until the gasket or packing ring 26 comes into contact with the lower surface of the chambered member 35. At the same time the valve 40 will be opened so as to throw a vacuum onto the member 24 by way of the pipe 29, and a vacuum on the chambered member 43 by way of the pipe 42. When 110 the vacuum reaches the desired limit, the plunger within the chamber 43 will be drawn down, thus bringing the clutch into play and causing the arm 64 to be rocked on its pivot 65. This will force down the 115

120

125

130

chambered member 35, so as to crimp the cover into place on the jar, and this downward movement will be transmitted to the bell member 24 which is held against the member 35 by reason of the vacuum existing within the chambers. Simultaneously the valve 40 will be reversed so as to disconnect the exhausting pipe 41 from the pipes 29 and 42, and simultaneously allow air to enter the chambers and thus break the vacuum. Thereafter, the cup member 24 will drop to its lowermost position and the chambered member 35 will rise.

I claim:

1. In a machine of the class described, the combination of a stationary receptacle support, a lower movable member arranged about said support, an upper shiftable member arranged above said support, means operatively connected for moving said lower member into engagement with said upper member to form a chamber about said support, means for creating a vacuum within said chamber, and means for moving said upper and lower members downward to cause the upper member to engage the closure of the receptacle, substantially as described.

2. In a machine of the class described, the combination of a stationary receptacle support, a lower movable member arranged to extend about said support, an upper movable member above said support, means operatively connected for moving said lower member into engagement with said upper member to form a chamber about said support, means for creating a vacuum within said chamber, means for simultaneously moving said upper and lower members downward to cause the upper member to engage the closure of the receptacle when a predetermined vacuum has been created in said chamber, substantially as described.

3. In a machine of the class described, the combination of a receptacle vacuum chamber, means for creating a vacuum within said chamber, a shiftable member, means exerting a force upon said shiftable member in counter-action to the force of the created vacuum, and means operatively connected for setting in operation means for breaking the vacuum within said receptacle chamber when a degree of vacuum has been created therein sufficient to overcome the counter-acting force exerted on the shiftable member, substantially as described.

4. In a machine of the class described, the combination of a receptacle chamber, means for creating a vacuum within said chamber, a shiftable member, means exerting a force upon said shiftable member in counter-action to the force of the created vacuum, means for varying the degree of the counteracting force, and means operatively connected for setting in operation means for

breaking the vacuum within said vacuum chamber when a degree of vacuum has been created therein sufficient to shift said shiftable member against the power of the counteracting force, substantially as described. 70

5. In a machine of the class described, the combination of a receptacle chamber, a shiftable member, connections from the main source of vacuum supply to one face of the shiftable member and to said chamber, an 75 arm connected to the shiftable member, means for applying pressure to said arm to counteract the vacuum force on the face of the shiftable member whereby said shiftable member is moved when the vacuum force is 80 greater than the pressure applied to said arm, and means actuated by the shifting of said member to set in operation means to break the vacuum in said chamber, substantially as described. 85

6. In a machine of the class described, the combination of a receptacle chamber, a shiftable member, connections from the main source of vacuum supply to one face of the shiftable member and to said chamber, an 90 arm connected to the shiftable member, means for applying pressure to said arm to counteract the vacuum force on the face of the shiftable member, means for varying the degree of pressure applied to said arm, and 95 means actuated by the shifting of said member to set in operation means to break the vacuum in said chamber, substantially as described.

7. In a machine of the class described, the 100 combination of a receptacle chamber, means for creating a vacuum within said chamber, means for breaking the vacuum in the chamber, means operated by the vacuum setting in operation the means for breaking the degree of vacuum created within said chamber after it has reached a predetermined degree, said means embodying a shiftable member, a lever connected to said shiftable member, and an adjustable weight upon said 110 lever, substantially as described. 105

8. In a machine of the class described, the combination of a receptacle chamber, means for creating a vacuum in said chamber, means for actuating said closure affixing 115 means, clutch mechanism controlling the operation of said closure affixing means, and means directly controlled by the vacuum in the chamber for actuating said clutch mechanism, substantially as described. 120

9. In a machine of the class described, the combination of a receptacle chamber, means for creating a vacuum in said chamber, means for affixing the closure to the receptacle, means for actuating said closure affixing means, clutch mechanism controlling the operation of said affixing actuating means, and means directly controlled by the vacuum in the chamber for operating said clutch mechanism, substantially as described. 125 130

10. In a machine of the class described, the combination of a fixed receptacle support, a lower shiftable member arranged about said support, an upper shiftable member above the support, means for moving the lower shiftable member into engagement with the upper shiftable member to form a chamber about said support, means for creating a vacuum within said chamber, receptacle closure affixing means carried by the upper shiftable member, and means for moving said upper shiftable member to effect the closure affixing operation when a predetermined degree of vacuum has been formed 15 in said chamber, substantially as described.
11. In a vacuum sealing machine, a chamber adapted to be vacuumized, and means operative by a reduction of pressure in said chamber for releasing the vacuum.
- 20 12. In a vacuum sealing machine, a closed chamber adapted to be opened, and means operative by a reduction of pressure in said chamber for releasing the vacuum therein so that the chamber may be opened.
- 25 13. In a vacuum sealing machine, a chamber adapted to be vacuumized, means in said chamber for applying pressure to the closure of a receptacle, and means operative by a reduction of pressure in said chamber for 30 releasing the vacuum.
- 35 14. In a vacuum sealing machine, a vacuumizable chamber adapted to contain a receptacle, means in said chamber for applying pressure to the closure of the receptacle, and means operative by a predetermined reduction of pressure in said chamber for releasing the vacuum therein.
- 40 15. In a vacuum sealing machine, a chamber adapted to be vacuumized and means operative by a predetermined reduction of pressure in the chamber for throwing into operation means for performing consecutively the several operations necessary to seal a receptacle *in vacuo* and to re-admit 45 the atmosphere to said chamber.
- 50 16. In a vacuum sealing machine, a vacuumizable chamber adapted to contain a receptacle to be sealed, means for closing said chamber, means for releasing the vacuum, and means operative by a reduction of pressure in said chamber for throwing into operation said vacuum releasing means, whereby the chamber may be opened.
- 55 17. In a vacuum sealing machine, a chamber adapted to be vacuumized, means for releasing said vacuum and means operative by a predetermined reduction of pressure in the chamber for throwing said vacuum releasing means into operation.
- 60 18. In a vacuum sealing machine, a chamber adapted to be vacuumized, means in said chamber for applying pressure to the closure of a receptacle, means for releasing the vacuum, and means operative by a predetermined reduction of pressure in said
- chamber for throwing said vacuum releasing means into operation.
19. In a vacuum sealing machine, a chamber adapted to be vacuumized, means for closing said chamber, and means operative 70 by a predetermined reduction of pressure in said chamber for throwing into operation means for performing consecutively the several operations necessary to seal a receptacle *in vacuo*, re-admit the atmosphere to the 75 chamber and permit the opening of the chamber.
20. In a vacuum sealing machine, a vacuumizable chamber adapted to contain the receptacle to be sealed, means in said chamber 80 for applying pressure to the receptacle closure, and means operative by a predetermined reduction of pressure in said chamber for throwing into operation said pressure applying means and thereafter releasing the 85 vacuum in the chamber.
21. In a machine for attaching closures to receptacles, a chamber adapted to be vacuumized, means in the chamber for attaching the closure to the receptacle, means operative 90 by a reduction in pressure within the chamber to a predetermined pressure to throw the attaching means into operation, and means for adjusting the means operated by the reduction in pressure to operate at varying 95 pressures.
22. In a machine for sealing closures to receptacles, a chamber adapted to be vacuumized, means in the chamber for pressing the closure to the receptacles, power driven 100 means for operating said pressing means, and automatically operated means for connecting said power driven means and said pressing means when a given degree of vacuum exists in said chamber.
23. In a machine for attaching closures to receptacles, a chamber adapted to be vacuumized, means in the chamber for attaching the closure to the receptacle, power driven means for operating said attaching 105 means, automatically operated means for connecting said power driven means and said attaching means when a given condition of vacuum exists in the chamber, and means for disconnecting said power driven means 115 and said attaching means at the end of the attaching operation.
24. In a machine for attaching closures to receptacles, a chamber adapted to be vacuumized, means in said chamber for attaching 120 the closure to the receptacle, means for operating said attaching means for one cycle of operations, and means operative by a reduction of pressure in the chamber for throwing said operating means into operation.
25. In a machine for attaching closures to receptacles, a chamber adapted to be vacuumized, means in the chamber for attaching the closure to the receptacle, means for oper- 125
- 130

ating said attaching means, means operative by a given reduction of pressure in the chamber for throwing said operating means into operation, said pressure operative means including means for throwing the operating means out of action at the end of the attaching operation.

26. In a machine for attaching closures to receptacles, a vacuumizable chamber adapted to receive the receptacle, means within the chamber for attaching the closure to the receptacle, and means operative by a predetermined reduction of pressure in the chamber for throwing said attaching means into operation.

27. In a vacuum sealing machine, a vacuumizable chamber adapted to contain a receptacle to be sealed, a valve between the vacuumizing means and the chamber and between the chamber and the atmosphere, and means operative by a predetermined reduction of pressure in said chamber for throwing into operation means for operating said

valve to cut off communication between the chamber and the vacuumizing means, and to establish communication between the chamber and the atmosphere.

28. In a vacuum sealing machine, a vacuumizable chamber adapted to contain a receptacle to be sealed, means in said chamber for pressing the closure against the receptacle, a valve between the vacuumizing means and the chamber and between the chamber and the atmosphere, and means operative by a predetermined reduction of pressure in said chamber for throwing into operation said pressing means and operating said valve to cut off communication between the chamber and the vacuumizing means and establish communication between the chamber and the atmosphere.

T. L. TALIAFERRO.
